CLAIM

The ornamental design for a saw, as shown and described.

DESCRIPTION

FIG. 1 is a perspective view of a saw showing an embodiment of our new design;

FIG. 2 is a right side view of the saw as shown in FIG. 1, the left side view of which is a mirror image of the right side view;

FIG. 3 is a front view of the saw as shown in FIG. 1;

FIG. 4 is a rear view of the saw as shown in FIG. 1;

FIG. 5 is a top view of the saw as shown in FIG. 1; and,

FIG. 6 is a bottom view of the saw as shown in FIG. 1. The broken lines in the drawings illustrate portions of the saw that form no part of the claimed design.

1 Claim, 4 Drawing Sheets
